(57) **CLAIM**

The ornamental design for a firearm magazine support mount, as shown and described.

DESCRIPTION

FIG. 1 is a top, rear perspective view of a firearm magazine support mount showing my new design;

FIG. 2 is a bottom, front perspective view thereof;

FIG. 3 is a rear side elevation view thereof;

FIG. 4 front side elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The disclosed firearm magazine support mount mates with and supports a firearm magazine or a other component of a firearm for assembling, servicing, cleaning, or other gunsmithing operation.
